INVENTOR.

Norman L. Normandi

BY Henry J. Webster
ATTORNEY

UNITED STATES PATENT OFFICE.

NORMAN L. NORMANDI, OF SAN FRANCISCO, CALIFORNIA, ASSIGNOR TO VICTOR R. WILL, OF LODI, CALIFORNIA.

DESIGN FOR A PERFUME-BURNING LAMP.

Application filed September 5, 1922. Serial No. 3,631. Term of patent 3½ years.

To all whom it may concern:

Be it known that I, NORMAN L. NORMANDI, a citizen of the United States, residing at San Francisco, in the county of San Francisco and State of California, have invented a new, original, and ornamental Design for a Perfume-Burning Lamp, of which the following is a specification, reference being had to the accompanying drawing, forming part thereof, in which—

Fig. 1 is a side view and Fig. 2 a front view, of a perfume-burning lamp, showing my new design.

I claim:

The ornamental design for a perfume-burning lamp, as shown.

NORMAN L. NORMANDI.

Witnesses:

A. B. MOSES,
FRANK H. CARTER.
